US0D1029837S

(12) **United States Design Patent** (10) **Patent No.:** **US D1,029,837 S**
(45) **Date of Patent:** **** Jun. 4, 2024**

(54) **KEYBOARD**

(71) Applicant: **ASUSTeK COMPUTER INC.**, Taipei (TW)

(72) Inventors: **Jau-Yi Wu**, Taipei (TW); **Ming-Chih Huang**, Taipei (TW); **Tong-Shen Hsiung**, Taipei (TW)

(73) Assignee: **ASUSTeK COMPUTER INC.**, Taipei (TW)

(**) Term: **15 Years**

(21) Appl. No.: **29/775,287**

(22) Filed: **Mar. 23, 2021**

Related U.S. Application Data

(63) Continuation-in-part of application No. 29/650,471, filed on Jun. 7, 2018, now Pat. No. Des. 918,910, which is a continuation-in-part of application No. 29/602,065, filed on Apr. 28, 2017, now Pat. No. Des. 822,673.

(57) **CLAIM**

The ornamental design for a keyboard, as shown and described.

DESCRIPTION

FIG. 1 is a perspective view of a keyboard showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines illustrating portions of the keyboard form no part of the claimed design; the dot-dash broken lines define the bounds of the claimed design and form no part thereof.

1 Claim, 5 Drawing Sheets
